UNITED STATES PATENT OFFICE.

CHARLES WACHTEL, OF NEW HYDE PARK, NEW YORK.

ELECTRIC BOUDOIR LAMP.

Application filed January 16, 1925. Serial No. 2,801.

One of the principal objects of this invention is to provide a small ornamental and readily portable self contained electric lamp adapted for household use.

5 Another important object of the invention is to provide a small portable self contained electric lamp with means whereby the lamp circuit will be interrupted when the lamp is placed on a table or other support, and 10 will be complete or closed when the lamp is lifted and carried about in the hand.

15 Another object of the invention is to provide means whereby the lamp circuit may be permanently closed so that it will not be affected by placing the lamp on a table or support, or lifted therefrom.

20 The lamp is illustrated in the drawings in the form of a candle stick, but of course it will be understood that it may be made up in any suitable form.

In the drawings:

Fig. 1 is a vertical central sectional view on the line 1—1 of Fig. 2 showing the lamp resting on a support and the lamp circuit 25 interrupted;

Fig. 2 a bottom plan view of the lamp with the bottom plate broken away, the auxiliary circuit closer being adjusted to open position;

30 Fig. 3 a fragmentary view similar to Fig. 2 with the auxiliary circuit closer in closed position;

Fig. 4 a detail perspective view of the circuit closing means;

35 Fig. 5 a fragmentary sectional view taken on the line 5—5 of Fig. 2 with the lamp resting on a support and the battery removed; and

Fig. 6 a view similar to Fig. 5 showing 40 the lamp lifted from the support.

The lamp is illustrated in the drawings in the form of a candle stick having a circular hollow base 1 open at its bottom and supporting a vertical hollow standard 2 of 45 slender ornamental form. The interior of

the standard is in communication with the interior of the base and serves as a passage for a circuit wire. At the upper end of the post is mounted an internally threaded lamp 50 socket 3 designed to receive the threaded end of a lamp bulb 4. The central terminal 5 of the bulb engages a fixed contact 6, mounted at the bottom of the socket and insulated from both the socket and the

standard. A circuit wire 7 leads downwardly from the fixed contact 6, through the standard and into the hollow base. The base and the standard are formed of metal, and are electrically connected through the socket 3 with the other lamp terminal. The 60 standard and base thus form part of the lamp circuit.

A flat electric battery 8 is located within the hollow base of the lamp and held in place by a retaining plate 9 which closes the 65 under side of the base. The plate 9 is removably held in place by means of a pair of diametrically located studs 10 carried by brackets 11 which are secured within the base. The studs 10 are formed with heads 70 and with reduced portions or necks adapted to engage in the reduced ends of key slots 12 formed in the retaining plate.

75 A block of insulation 13 is secured within the base at one side of the battery and against the inner side wall of the base. The block 13 is formed with a flat face directed toward the battery, and fixed to said face are two terminal plates 14 and 15 respectively. These plates are arranged flush 80 with each other upon the face of the block 13 and their opposed end edges are spaced apart and diagonally formed to provide a downwardly tapering V-shaped gap between the plates. The plate 15 is formed with an 85 arcuate extension 16 which overlies an insulating strip 17 upon the inner side of the base. This extension is inturned at its outer end and is adapted to be engaged by a resilient terminal strip 18 extending from the 90 battery. The other terminal strip 19 of the battery makes contact with the inner side 95 of the base. The circuit wire 7 is connected at its lower end to the terminal plate 14 as at 20. A lamp and battery circuit is thus formed including the wire 7 and the standard and base of the lamp. This circuit is, however, broken by the gap between the 100 terminal plates 14 and 15.

105 A circuit closing plunger 21 is mounted for vertical reciprocation within a guide bore 22 in the insulation block 13 and extends downwardly through an opening in the plate 9. This plunger is formed with a lateral extension 23 which extends 105 through a slot in the block and into the gap between the terminal plates 14 and 15. The extension 23 tapers downwardly in the

form of a wedge corresponding to the slant of the opposed ends of the terminal plates, and when the plunger is in its lower position the extension 23 is adapted to bridge the gap between the terminal plates and make a close electrical contact with both plates. The extension 23 is of conducting material and the battery and lamp circuit is thereby closed and the lamp bulb illuminated. A coiled spring 24 is interposed between the upper end of the plunger 21 and the upper end of the bore 22 and tends to press the plunger down to circuit closing position. In its circuit closing position the lower end of the plunger extends below the bottom of the lamp base as shown in Fig. 6. When the lamp is placed upon a support the plunger is forced upwardly against the resistance of the spring 24 by the weight of the lamp. The extension 23 is then carried up into the wide portion of the gap between the terminal plates to break its contact with the plates. The circuit is thus automatically broken and the light extinguished. By merely lifting the lamp from the support the circuit will again be automatically closed and the bulb illuminated, by the spring 24 forcing down the plunger.

In order to provide for illumination when the lamp is resting upon a support, auxiliary circuit closing means are provided. Extending across the gap between the terminal plates 14 and 15 is a circuit closer in the form of a leaf spring 25 of conducting material. The spring 25 is secured at one end as at 26 to the terminal plate 14. The opposite end of the spring is free and the resilience of the spring tends to press said free end against the terminal plate 15 to automatically connect said plate with the plate 14 and close the circuit. A lever 27 is pivoted as at 28 in an opening extending through the block 13 and is provided at its inner end with an insulation tip 29 adapted to engage the free end of the leaf spring 25. The outer end of the lever 27 extends outwardly through a slot in the side of the base and is formed with an operating knob. The spring 25 is bowed at the center to provide clearance for the plunger extension 23 and is formed at its free end with a contact hump 30 extending toward the terminal plate 15. When manually shifted to the position shown in Fig. 2 the lever 27, through the engagement of its insulation tip with the contact hump of the spring, forces the spring away from the contact plate 15 and opens the circuit. This is the normal position of the lever and in order to reach this position the tip snaps over the peak of the contact hump. The spring then holds the lever yieldingly in this position. When the lever is manually shifted to the position shown in Fig. 3 the tip snaps to the opposite side of the con-

tact hump. This frees the spring and it snaps to circuit closing position, connecting the terminal plates 14 and 15. Permanent illumination is thus provided for regardless of the position of the lamp.

The insulation block 13 carrying the circuit closing means is located inwardly of one of the brackets 11 and is secured in place by a screw 31 extending through the bracket and upwardly into the block. It will be observed that the block, the terminal plates and both circuit closing means form a unit which may be readily inserted and secured in place and may be easily removed after withdrawing the screw 31. The bottom plate 9 is readily removable by slightly rotating it in order to free it from the retaining studs 10. Studs 32 are provided on the plate to facilitate turning it. When the plate is removed, the battery is only frictionally held and may be easily withdrawn from the base.

What I claim is:

1. A circuit closing device comprising a plunger; means supporting said plunger to reciprocate vertically; spaced terminal members adapted to be connected by the plunger in its lower position to close the circuit; a spring tending to move the plunger down to its lower position, the plunger being formed with a projecting lower end adapted to be engaged to press the plunger out of contact with said terminal members against the spring resistance; an auxiliary circuit closer in the form of a leaf spring tending by its resilience to connect said terminal members and close the circuit independently of the plunger; and manually shiftable means adapted when shifted to one position to move and hold the leaf spring in a circuit opening position and when shifted to another position to permit said spring to move to a circuit closing position.

2. A circuit closing device comprising a block of insulating material; a pair of terminal plates mounted upon said block and spaced apart to form a gap; a plunger mounted in said block to reciprocate vertically and provided with an extension adapted in the lower position of the plunger to bridge said gap between the terminal plates; a spring to move the plunger down to close the circuit, the plunger being formed with a projecting portion adapted to be engaged to move the plunger out of contact with the terminal plates to break the circuit; an auxiliary circuit closer in the form of a leaf spring fixed at one end to one of the terminal plates, extending across said gap and tending by its resilience to force its opposite end against the other terminal plate to close the circuit; and a lever pivoted to the said block to engage the leaf spring and adapted to be shifted to one position to move and hold the free end of the leaf spring out

of circuit closing position and to be shifted to another position to permit the leaf spring to move to its circuit closing position.

3. A circuit closing device comprising a block of insulating material; a pair of terminal plates mounted upon said block and spaced apart to form a V-shaped gap opening upwardly; a plunger mounted in the block to reciprocate vertically; an extension formed on the plunger to bridge said gap between the terminal plates to close the circuit when the plunger is in its lower position; and means mounted on said insulation block and manually operable to close the circuit independently of the plunger.

4. A circuit closing device comprising a pair of spaced terminal members; shiftably mounted circuit closing means to connect said terminal members and close the circuit, said circuit closing means being shiftable to a position to open the circuit and tending to automatically return to circuit closing position; and manually operable means to connect said terminal members and close the circuit independently of the first circuit closing means.

In testimony whereof I hereunto affix my signature.

CHARLES WACHTEL.
